UNITED STATES PATENT OFFICE.

JAKOB ADRIAN, OF OBERURSEL, NEAR FRANKFORT-ON-THE-MAIN, GERMANY.

DRIVING DEVICE.

1,117,749.

Specification of Letters Patent. Patented Nov. 17, 1914.

Application filed October 17, 1910. Serial No. 587,601.

To all whom it may concern:

Be it known that I, JAKOB ADRIAN, a subject of the German Emperor, and a resident of Oberursel, near Frankfort-on the Main, 5 Germany, have invented certain new and useful Improvements in Driving Devices, of which the following is a specification.

The present invention relates to improvements in driving or power transmission devices in which the prime driver is a lever actuated by a cam. In driving devices of this character it has been commonly necessary to employ cams of large diameter, but as the circumferential velocity of such cams increases with increase in diameter of the cam disks and it is dangerous to have such velocity exceed a certain limit, it has been heretofore impossible to employ cam disks which did not have a comparatively low 20 velocity.

The object of the present invention is to provide a construction by which the actuating cam may be given a much higher velocity than those commonly employed.

25 The drawing illustrates one embodiment of the invention adapted for driving the needle of a shoe sewing machine.

Referring to the drawing, 1 designates a cam disk which is mounted on a suitable 30 driving shaft 2 and provided in one face with a cam groove 5. A roller stud 4 on a lever 3 works within the cam groove 5 and at one end said lever is connected with a toothed actuator bar 10 that meshes with 35 a gear sector 12 supported on a bearing 11 and carrying the curved needle 13. As shown the pivot or fulcrum of the lever 3 is connected by a vertically guided rod 6 with an arm 7 adapted to be oscillated by 40 an eccentric 9 on a driving shaft 8.

The parts are so arranged that the fulcrum of the lever is moved vertically by the action of the eccentric 9 while the body of the lever is being rocked about such 45 fulcrum by the action of the cam, the direction in which the fulcrum is thus moved at any instant being opposite that in which the disk 1 is then moving the lever.

Having thus described the invention what is claimed is,

1. In a power drive mechanism, the combination of an actuator 10, a lever connected with the actuator, a rotary cam acting upon the lever between its fulcrum and the actuator, and means for moving the lever fulcrum simultaneously with the actuation of the lever by the cam and in a direction opposite that in which the cam moves the lever. 50

2. In a power drive mechanism, the combination of a lever, a rotary cam engaging the lever at one side of its fulcrum, and an eccentric acting to shift the lever fulcrum simultaneously with the movement of the lever by said cam and in a direction opposite that in which the lever is moved by the 55 cam.

3. In a power drive mechanism, the combination of a lever having its fulcrum adjacent one end, a rotary cam engaging the lever at an intermediate point in its length 70 to rock it about the fulcrum, an eccentric adapted to positively move the fulcrum simultaneously with the rocking of the lever by said cam and in a direction opposite that in which the latter moves the lever. 75

4. In a power drive mechanism, the combination of a lever, a rotary cam engaging the lever and adapted to rock it about the fulcrum, an eccentric, and a link connected with the fulcrum support of the lever and 80 engaging the eccentric, the latter being so related to the cam that the fulcrum of the lever will be positively shifted as the lever is rocked by the cam, the direction of movement of the fulcrum being opposite that in 85 which the lever is rocked.

In testimony whereof I have signed my name to this specification in the presence of two subscribing witnesses.

JAKOB ADRIAN.
